CLAIM

I claim the ornamental design for a universal cable installation tool, as shown and described.

DESCRIPTION

FIG. 1 is a perspective view of a universal cable installation tool;

FIG. 2 is a side view of the universal cable installation tool of FIG. 1;

FIG. 3 is a bottom view of the universal cable installation tool of FIG. 1;

FIG. 4 is a top view of the universal cable installation tool of FIG. 1;

FIG. 5 is a perspective view of the universal cable installation tool according to another embodiment of the invention.

FIG. 6 is a side view of the universal cable installation tool of FIG. 5;

FIG. 7 is a bottom view of the universal cable installation tool of FIG. 5; and,

FIG. 8 is a top view of the universal cable installation tool of FIG. 5.

Items shown in broken lines are for illustrative purposes only and form no part of the claimed invention.

The universal cable installation tool is shown with a symbolic break in its length. The appearance of any portion of the article between the break lines forms no part of the claimed design.
